To all whom it may concern:

Be it known that I, FRANZ YOKEL, of Meriden, in the county of New Haven and State of Connecticut, have invented a new Design for a Slab for Table-Tops, (Case E;) and I do hereby declare the following, when taken in connection with the accompanying drawing and the letters of reference marked thereon, to be a full, clear, and exact description of the same, o and which said drawing constitutes part of this specification and represents a top or face view of a slab for a table-top illustrating the design.

This invention relates to a design for a slab for a table-top, and the design consists in the configuration and ornamentation as shown in the accompanying illustration. The central portion of the slab is in the form of two rectangles, each surrounded by a border of corresponding rectangular form, and which are connected at two of their angles by trefoils

On each side of each rectangle is an upwardly turned scroll C, having reversely curved lines upon it, meeting at the center, and lying upon a straight band D, having a scroll termination, the curves of the band and upwardly turned scrolls surmounted by a shell E, forming the angles of the frame. On each outer side of the frame rises an open foliated scroll, surmounting fret-work, all as shown in the accompanying illustration.

I claim—

The design for a slab for table-tops as herein shown and described.

In testimony whereof I have signed this specification in the presence of two subscribing witnesses.
